CHARLES D. MONTAGUE, OF NEW YORK, N. Y.

COMBUSTION METHOD AND FURNACE COMBUSTION CHAMBER

Application filed June 25, 1925. Serial No. 39,477.

The invention relates to a method of burning fuel and to an instrumentality for practicing the method efficiently. In its mechanical aspects the invention relates in general to 5 a novel combustion chamber of general application wherever a heating unit is required, and the invention relates specifically to a unit formed of fire resistant material designed to constitute an insert to be positioned in the fire 10 pot of a furnace, such as a domestic heating furnace, of the types which are constructed or modified to burn a hydrocarbon fuel, usually discharged into the same by some form of spray ejector fuel nozzle type of burner. 15 In similar constructions now known it is a usual practice to direct the discharge from the burner nozzle either directly into the fire pot zone or directly against a metallic hot plate positioned in the fire pot to constitute 20 a hot target against which the fuel is directed.

Such constructions have not proved to be commercially satisfactory among other reasons due to the fact that the combustion act 25 was not completed prior to the contact of the burning gases against the water jacketed walls outlining the furnace. The fact that soot and other carbon deposits are found in the outlet flue and in contact with the water 30 jacketed walls shows that with the known forms of such constructions some of the more difficultly oxidizable hydrocarbon complexes in the fuel were not completely oxidized.

The primary object of the invention is to 35 provide for a complete, or at least a substantially complete, combustion of all of the hydrocarbon complexes present in the fuel under such conditions as will promote a rapid and complete oxidation before the hot products 40 of combustion are brought into the presence of the water jacketed and other walls containing the water, air or other heat extracting mediums usually employed in devices of this character.

Broadly, this phase of the invention is attained by providing a long combustion chamber between the fuel discharging nozzle and the point or zone in the furnace where it is desired to abstract heat from the flaming 50 products of combustion.

As it is of course impossible to provide a long, straight combustion zone within the narrow confines of the usual house furnace, the invention herein features a combustion chamber formed of telescopic tubes arranged 55 to provide a long tortuous passageway for the burning fuel and which arrangement incidentally provides for a mutual insulating from excessive heat losses of each inner conduit by the hot jacketing effect of its next 60 adjacent outer conduit.

It is apparently required in order to insure a quick ignition of the more difficultly vaporizable hydrocarbon complexes that a large 65 amount of heat be concentrated on the fuel during the initial stages of the combustion act.

Accordingly, another object of the invention and featuring the tortuous passageway herein disclosed, is to provide a baffle arranged to direct the heat backwardly on to the incoming unburned fuel so as to raise the temperature thereof rapidly and thereafter permit a relatively long time duration for the subsequent stages of the combustion act; and 75 at all times maintain in the combustion zone conditions which will not tend to lower the temperature of the burning gases during their passage through the combustion zone.

In devices of this character heretofore used 80 it has been usual to utilize all of the combustion supporting air for the purpose of spraying the fuel and this necessitated the use of relatively large blowers for handling the large volume of air necessary to burn the fuel. 85 This was objectionable in that it necessitated the use of large fans and correspondingly large motors for driving the same with the resulting heavy consumption of electric current and the creation of noise which has rendered such devices unpopular for domestic use. Further, it is believed that this manner of feeding all of the air through the burner deleteriously affected the combustion act in that the large volume of air present tended 90 to cool the hydrocarbons at the point where the highest temperature was desired.

Accordingly, another object of the invention is to provide for a sequential and gradually increasing rate of feeding of the com- 100

bustion supporting air through the incoming end of the combustion chamber and to distribute the air at spaced apart points adjacent this end in order to provide for a more perfect combustion than has been possible heretofore in this art.

Another object of the invention is to provide for economy in the original cost and in the cost of operation of the fan, motor, and other apparatus necessary to insure the vaporization, spraying or volatilization of the hydrocarbon discharged from the burner and incidentally to minimize the amount of air necessary to be handled by such apparatus.

Various other objects and advantages of the invention will be in part obvious from a consideration of the method features of the disclosure and from an inspection of the accompanying drawings, and in part will be more fully set forth in the following particular description of one method of practicing the invention and in the inspection of a furnace embodying certain mechanical features of my invention, and the invention also consists in certain new and novel modifications of the preferred method and other features of construction and combination of parts hereinafter set forth and claimed.

In the accompanying drawings:—

Figure 1 is a view in vertical axial cross section of the lower portion of a household heating furnace provided with an insert constituting a preferred embodiment of the invention.

Figure 2 is a horizontal sectional view taken on the broken line 2—2 of Figure 1 looking downwardly.

Figure 3 is an enlarged plan view of the air distributor and drip trough shown in reduced vertical section at the lower portion of Figure 1.

Figure 4 is a view in front end elevation of the air distributor shown in Figure 3; and

Figure 5 is a transverse sectional view taken on the line 5—5 of Figure 3.

In the following description and in the claims, parts will be identified by specific names for convenience of expression but they are intended to be as generic in their application to similar parts as the art will permit.

In the drawings there is shown a furnace including a water jacket shell 10 mounted on a concrete base 11 and provided with the usual coal supplying opening 12 and with the usual ash pit opening at 13. The shell 10 encloses pockets 14 containing water, steam, air or other heat abstracting medium usual in furnaces of the type now in general use for heating household and industrial buildings.

The present disclosure is intended to illustrate the application of the invention to the household type of furnace and the combustion forming chamber herein featured is formed as a separate insert designed to be

readily installed in conventional forms of such furnaces. There is disclosed an L-shaped conduit 15 including a horizontally disposed fuel receiving leg 16 projecting forwardly through the ash pit opening 13 and a vertically extending cylindrical leg 17 projecting upwardly and centrally into the usual fire pot space of the furnace. The horizontal portion 16 is preferably rectangular in vertical cross section or is otherwise designed so as to provide the maximum sized chamber within the dimensions permitted by the ash pit opening when the usual door therefor is removed. The front of the leg 16 is closed by means of a front plate 18 provided centrally thereof with an opening 19 closed by a cover plate 20. Through the plate extends a burner 21 preferably of the adjustable spray nozzle type and which burner is supplied with hydrocarbon fuel, such as crude oil, through the fuel intake pipe 22 and with air under pressure admitted through an air supplying pipe 23, as is usual in constructions of this character, except that the whole assembly is smaller than is usual with this size furnace.

The present disclosure features a distinction over similar devices now known in that while the air supplied through the burner nozzle is under sufficient pressure and is present in sufficient volumetric amounts necessary to insure an effective spraying of the liquid fuel particles into the conduit, it is not intended that the air supplied through the nozzle be in sufficient amounts to supply the requisite amount of oxygen necessary to insure complete combustion of the hydrocarbon complexes present.

In order to supply the necessary amount of air an auxiliary air supply supplements the air supplied by the burner but this supplemental air is not necessarily under pressure but is supplied by the natural draught created during the operation of the device disclosed. For this purpose the bottom of the leg 16 of the conduit is outlined by an air distributor 24. This air distributor, as particularly noted from Figures 3, 4 and 5, comprises essentially a metal foundation piece providing a support for a row of fire brick forming the major portion of the bottom of the combustion chamber. The metal foundation includes a wide spreading V-shaped metal shelf 25 provided in the instant case with two parallel lines of air conduits 26 in the form of short open end tubes projecting above the V-shaped shelf. Opposite edges of the metal shelf are supported from the bottom of the ash pit on L-shaped uprights 27, the horizontally extending flanges 28 of which are designed to fit between the vertical walls outlining the ash pit and the vertically depending flanges 29 of which constitute feet for supporting the shelf above the bottom of the ash pit and thus provide an air passage.

way 30 between the metal shelf and the bottom of the ash pit. Positioned on top of the metal shelf is a series of flat fire bricks 31, one for each transversely positioned pair of air conduits 26, positioned over the same as indicated in dotted outlines in Figures 3, 4 and 5, longitudinally spaced apart to provide air vents 32 for supplying combustion supporting air at a plurality of spaced apart points along the length of the conduit 16. From this construction it is apparent that air can enter from the outside and can travel beneath the trough 25, and through the conduits 26 in the direction of the long arrows into the combustion chamber at spaced apart points therein. The shelf 26 also acts as a drip pan for receiving any liquid particles which may fall from the combustion chamber and such drip may be discharged through a drip opening 33 in the front wall 34 defining the front end of the air distributor.

Encircling the upper portion of the conduit arm 17 is a second cylindrical shaped conduit 35 which extends above the top of the conduit 17 and is closed by means of a closure plate 36. The closure 36 is in the form of a heavy thick plate of fire resistant material and will be referred to specifically as a baffle for reflecting heat downwardly through the combustion chamber 15 towards the incoming air discharged upwardly through the conduits 32.

The conduit 35 rests on spaced apart risers 37 arranged to provide a plurality of circumferentially spaced flaming fuel discharging conduits 38 therebetween as shown in Figure 2. The conduit 35 is of less diameter than the internal diameter of the shell 10 so as to provide an annular discharging passageway 39 between the second conduit and the outer lining furnace metal shell 10.

It is appreciated that this construction forms an extremely long, tortuous passageway and the object of the construction is to provide a length of combustion chamber between the burner and the point of discharge of the hot gases against the water jacketed walls which will be relatively long. This length must of course vary with different sizes and conditions of furnaces and is herein identified in certain of the claims as having a length materially greater than any other dimension but it is the intent to provide such length of passageway as will effect a sufficient time lapse to insure complete combustion of all of the hydrocarbon particles before the burned gas is brought in contact with the cooling effect of the water jacketed shell.

It is assumed that the lighter more volatile hydrocarbon complexes are promptly burned closely following the discharge of the same from the burning nozzle and that these burning gases will tend to heat the more difficultly volatilizable hydrocarbon complexes at points farther on in the combustion chamber at

which points the fresh supply of air is admitted through the auxiliary air supplying vents. The hot gases striking the baffle appears to slow down what might otherwise be the normal rate of travel of the burning gases and there results an intensely heated but quiet burning of the fuel.

By means of a device such as is herein disclosed it has been found possible to utilize all or substantially all of the crude oil used with an unusually high efficiency and the producing of a temperature in the combustion chamber higher than has been found practical heretofore in devices of this character. Little or no soot is formed in the fuel passageways and every effort is made to minimize any cooling of the burning gases up to its point of engagement with the shell outlining the furnace.

The device disclosed also features economy in the size of air blower heretofore regarded as necessary in such constructions with a resultant reduction in amount of electric energy necessary to driving such blower.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a household heating furnace, the combination of means forming a long tortuous combustion chamber, a hydrocarbon burner discharging fuel and a limited amount of air into one end of said long chamber, means intermediate the ends of said chamber for supplying combustion supporting air, means at the opposite end of said chamber and in spaced relation to said burner and air supplying means for abstracting the heat of combustion from the burning fuel discharged from the combustion chamber being formed of a heat refractory material to minimize heat losses therethrough, said chamber having a length materially greater than either of its other two dimensions and having a length sufficient to cause the hydrocarbons discharged into the same by the burner to be completely burned before subjected to the cooling effect of said heat abstracting means.

2. In a furnace having a water jacket shell, a plurality of telescopic tubes of fire resistant material coacting to provide a tortuous passageway including two parallel vertically extending passageways constituting a long combustion chamber, a burner discharging into the innermost tube, and the outermost tube discharging against the inner wall of said water jacket shell.

3. In a household heating furnace, the combination of an L-shaped conduit, a burner

discharging into one leg of said conduit, a tubular shell of fire resistant material having its upper end closed and its lower end open and telescoping the other leg of said L-shaped conduit and forming therewith a tortuous passageway constituting a combustion chamber and a furnace including a water jacketed shell enclosing said last named conduit and adapted to receive the heat of combustion discharged therefrom.

4. An insert for a furnace, said insert formed of heat resistant material, comprising a horizontally extending combustion chamber discharging at one end into an upstanding conduit, open at its upper end and adapted to receive flaming fuel from the combustion chamber at its lower end, a second conduit insulated from the combustion chamber, surrounding and spaced from the upper end of the first named conduit and extending above the same, a baffle plate of fire resistant material constituting a closure for the top of the second conduit, and means for supporting the lower portion of the second conduit and coacting to provide ports for discharging the hot products of combustion from the bottom of the second conduit.

5. In a household heating furnace, the combination with an outer, metallic water jacketed shell, a combustion chamber contained within said shell and comprising a tubular insert of fire resistant material providing a tortuous passageway with its discharge end adjacent the bottom of the inner side of said water jacketed shell, and with its intake end positioned below said shell, and said combustion chamber outlined up to its discharge end by the fire resistant material of said tubular insert, and a burner discharging into said intake end.

6. In a furnace, the combination of means forming a long tortuous combustion chamber; a hydrocarbon burner discharging into one end of said long chamber, means at the opposite end of said chamber and in spaced relation to the burner for abstracting the heat of combustion from the burning fuel discharged from the combustion chamber, said chamber having a length materially greater than either of its other two dimensions and having a length sufficient to cause the hydrocarbons discharged into the same by the burner to be completely burned before subjected to the cooling effect of said heat abstracting means, a plurality of air vents positioned adjacent the burner end of said chamber and spaced along the length thereof for supplying combustion supporting air to said chamber at a plurality of points and a portion of said chamber forming means between said air vents and said abstracting means being vertically disposed and subjected on opposite sides thereof directly to the heat of combustion in said chamber from the burning gases passing along said sides.

7. In a furnace, the combination of an L-shaped conduit, a burner discharging into one leg of said conduit, a closed end conduit telescoping the other leg of said L-shaped conduit and forming therewith a tortuous passageway constituting a combustion chamber, a shell enclosing said last named conduit and adapted to receive the heat of combustion discharged therefrom, and means for supplying combustion supporting air at a plurality of points through the bottom side of the first named leg of the L-shaped conduit.

8. An insert for a furnace, said insert formed of heat resistant material, comprising an upstanding conduit, open at its upper end and adapted to receive flaming fuel at its lower end, a second conduit supported at its lower end surrounding and spaced from the upper end of the first named conduit and extending above the same, a closure for the top of the second conduit supported thereon, means at the lower portion of the second conduit constituting a plurality of circumferentially spaced apart ports for discharging hot products of combustion from the bottom of the second conduit, and means for discharging burning gases into the lower end of the upstanding conduit.

9. In a device of the class described, an air distributor constituting the bottom of a combustion chamber and comprising a metal shelf perforated to form air conduits, uprights supporting the shelf to provide an air passageway beneath the shelf and open at one end, and fire bricks spaced apart on the top of the distributor and positioned above the shelf to permit the passage therebetween of air drawn through the air conduits in the metal shelf.

10. In the art of burning a complex hydrocarbon fuel, the method which consists in discharging into the combustion zone and under pressure a stream of fuel particles with air in a volumetric amount insufficient to support the combustion of the hydrocarbons present and causing said pressure stream by its suction effect to draw into said fuel stream a plurality of air streams spaced apart longitudinally of the path of travel of the burning fuel while insulating said zone to minimize heat losses and reduction in temperature of the burning gases, causing said streams to move under natural draft and in volumetric capacity capable of supplying an amount of air sufficient to insure complete combustion of all of the combustible complexes present, causing all of said air streams to enter the fuel stream adjacent the intake end of the combustion zone and in spaced relation to its discharge end while subjecting the burning gases in the upper part of said combustion zone to heat reflected downwardly towards the incoming natural draft air streams, and maintaining

said heat at a temperature greater than the combustion point of the burning gases.

11. In the art of burning a complex hydro-carbon fuel, the method which consists in spraying into the lower intake end of a long combustion zone a stream of liquid fuel particles with air under pressure and in a volumetric amount insufficient to support the combustion of the hydrocarbons present and drawing into said fuel stream a plurality of air streams not under pressure but spaced apart longitudinally and horizontally of the path of travel of the burning fuel, causing said streams to coact in supplying an amount of air sufficient to insure complete combustion of all of the combustible complexes present, causing all of said air streams to enter the fuel stream adjacent the intake end of the combustion zone and in spaced relation to its discharge end, subjecting said fuel and air streams at a point intermediate the ends of the combustion zone and adjacent its lower intake end to the heat reflected back and downwardly through the combustion zone from a subsequent stage of the combustion act to cause a rise in temperature of the cold air and incoming liquid fuel and thus cause the same to be heated to a point higher than the combustion point of the fuel before the flaming fuel reaches the upper portion of the combustion zone.

12. In a household heating furnace, the combination of means forming a long, tortuous combustion space outlined by refractory material, said means including an up-standing tubular wall and a top of refractory material constituting a baffle facing the intake end of the combustion space and adapted to be heated to incandescence by the burning gases passing through the space, means for supplying fuel and combustion supporting air to the lower intake end of said space, means positioned beyond the discharge end of said combustion space for abstracting heat from the hot gases discharged from said chamber, and said combustion space between said lower fuel intake end and the heat abstracting means being entirely closed thereby to prevent the introduction into the combustion space of any fluid except that introduced at said lower fuel intake end.

Signed at New York, in the county of New York and State of New York, this 18th day of June, A. D. 1925.

55 CHARLES D. MONTAGUE.
